LOOSE LEAF BINDER

Fred D. Wedge, Lombard, Ill., assignor to Wilson-Jones Company, Chicago, Ill., a corporation of Massachusetts

Application October 8, 1934, Serial No. 747,259

7 Claims. (Cl. 129—1)

This invention relates to a loose leaf binder of the channel back type adapted to hold one or more sheet retaining members.

It is an object of this invention to provide a channel back binder in which the sheet retaining member may be inserted into the channel member with a minimum of effort. It is a further object of this invention to provide a binder of this type wherein the sheet retaining unit is securely held against accidental displacement. Other objects of this invention will become apparent upon reading the following description, taken in conjunction with the accompanying drawings in which

15 Figure 1 is a perspective view of a loose leaf binder embodying the invention;

Figure 2 is a cross sectional view taken along the line II—II;

Figure 3 is an exploded view of the channel member and the sheet retaining structure of the binder;

Figure 4 is a perspective view of a modified embodiment of the invention;

Figure 5 is a top plan view of one corner of the binder shown in Figure 4 with a portion of the cover broken away; and

Figure 6 is an exploded view of one of the channel members and the associated sheet retaining unit of the binder shown in Figure 4.

30 In the drawings, the reference numeral 2 indicates a back section to the opposite edges of which covers 3 and 4 are secured. A metal channel member 5 is secured to the back section in any suitable manner. In the preferred form, 35 the channel member is secured to a flat plate member 6 by means of a plurality of rivets 7. A strip 8 of leather, fabric or other suitable material secured between the channel member 5 and the flat plate member 6 projects beyond the edges 40 of the plate member and is secured to the back section 2 by means of stitching, indicated at 9 in Figure 1.

The side walls 10 of the channel member 5 are recessed, as indicated at 11, and each recess 45 is provided with a tongue 12 projecting partially across the recess 11. The sheet retaining unit includes a pair of complementary somewhat resilient prong carrying bars 13. The bars 13 are duplicates, but are arranged in opposed relationship in the binder. Each bar 13 has secured thereto a plurality of prongs 14 upon which a plurality of sheets 15 may be impaled. Each bar 13 is apertured, as indicated at 16, Figure 3, to receive the end of the prongs 14 carried by the 50 opposite bar. The prongs 14 are preferably 55

arched to enable the sheets 15 to lie substantially flat when the binder is opened.

Each bar 13 has an upstanding flange 17 to facilitate alignment of the sheets 15 with respect to the prongs. If desired, the sheets 15 may be in the form of a bound pamphlet instead of being loose. The bars 13 are provided with a plurality of loops or straps 18 projecting therefrom. These loops may be integral with the bars, as shown in Figure 3, or may be formed separately and secured to the bars in any suitable manner. The loops 18 are narrow enough to be received in the recesses 11 beyond the projecting ends of the tongues 12. After the sheet retaining unit has been inserted into the channel member, a slight 10 longitudinal movement causes the tongues 12 to engage the loops or straps 18 to hold the sheet retaining unit in the binder.

One end of each bar 13 is turned inwardly, as indicated at 19, to facilitate longitudinal movement of the sheet retaining unit. An embossed stop member 20, positioned adjacent one end of the upper resilient bar 13, abuts the end of the wall 10 of the channel member 5 when the tongues 12 are in engagement with the loops 25 18 to prevent accidental longitudinal movement of the sheet retaining unit with respect to the binder. When it is desired to remove the sheet retaining unit from the binder, the end of the bar 13 is pressed inwardly to move the stop member 20 out of the plane of the wall 10 of the channel member. The stop member 20 is duplicated on the opposite resilient bar 13 so that the sheet retaining unit may be reversed in the binder without losing the advantage of the stop member 20. 30

In the modified embodiment of the invention illustrated in Figures 4, 5 and 6, the single sheet retaining unit is replaced by a plurality of sheet retaining units of less capacity. In this embodiment the channel members 5' are secured to a strip 21 of leather or fabric by means of a plurality of prongs 22 struck out of the back wall of the channel member 5', as shown in Figure 5.

It is not deemed necessary to describe the structure of the modified form of sheet retaining unit in detail, inasmuch as it is substantially similar to the structure previously described. Because of the difference in size, the bars 23, corresponding to the bars 13 of the preferred embodiment, are provided with integral sheet retaining prongs 24. These prongs are not arched, as in the case of the prongs 14, because the number of sheets that may be carried by these individual units is not sufficient to necessitate curved prongs 45 50 55

to allow the sheets to lie flat. The somewhat resilient bars 23 are each provided with a stop member 25, corresponding with the stop member 20, adjacent one end thereof. The operation of 5 the modified form is exactly the same as that of the preferred form of binder previously described.

Although I have described preferred embodiments of my invention in considerable detail, it will be understood that many modifications or 10 changes may be made in the structure described without departing from the spirit or scope of my invention. Accordingly, I do not desire to be restricted to the exact structure described, except as limited by the appended claims.

15 I claim:

1. In a loose leaf binder, a channel member, a sheet retaining member receivable in said channel member, said channel member and said sheet retaining member each having a pair of upstanding side walls, a loop projecting from a side wall 20 of one of said members, and a tongue on the adjacent side wall of said other member adapted to engage said loop to hold said sheet retaining member in said channel member.

25 2. In a loose leaf binder, a channel member, said channel member having a pair of upstanding side walls, a tongue integral with one of said side walls, a sheet retaining unit adapted to be contained in said channel member, and means 30 on said sheet retaining unit engageable with said tongue to hold said sheet retaining unit in said channel member.

3. In a loose leaf binder, a channel member, the side walls of said channel member being recessed, a tongue projecting partially across each 35 of said recesses, a sheet retaining unit, means projecting from said sheet retaining unit insertable in said recesses and engageable with said tongues

to hold said sheet retaining unit in said channel member.

4. In a loose leaf binder, a channel member, the side walls of said channel member being recessed, a sheet retaining member having integral loops adapted to be received in said recesses, a tongue projecting into each of said recesses and engageable with said loops, and means on said sheet retaining unit engageable with one end 10 of said channel member to prevent accidental separation of said tongues and loops.

5. In a loose leaf binder, a channel member, the side walls of said channel member being recessed, a sheet retaining unit, projections extending outwardly from said sheet retaining unit, 15 said sheet retaining unit being slidable in said channel member when said projections are positioned in said recesses, and means on said channel member engageable with said projections to hold said sheet retaining unit in said channel 20 member.

6. In a loose leaf binder, a channel member, the side walls of said channel being recessed, a sheet retaining unit provided with projections, 25 said sheet retaining unit being slidable in said channel member with said projections positioned in said recesses, and means to prevent accidental sliding movement of said sheet retaining unit.

7. A loose leaf binder comprising a back section, a plurality of channel members secured to 30 said back section, each of said channel members having recessed side walls and being adapted to receive a sheet retaining unit, said sheet retaining units having projections entering said recesses, and means on said channel members co- 35 operating with said projections to retain said sheet retaining units in said channel members.

FRED D. WEDGE.
